METHOD OF ABRADING CRANKSHAFTS

Frank Postma, Ridgewood, N. J.

Application September 17, 1937, Serial No. 164,390

2 Claims. (Cl. 51—278)

This invention relates to a method of abrading crankshafts, and has more particular reference to an improved method of abrading the journals of engine crankshafts for the purpose of truing and/or polishing such journals after they have become unevenly worn and scored from any cause such as continued operation of the engine with defective or burned out bearing liners.

In truing and polishing the journals of engine crankshafts, as heretofore practiced, it has been necessary to completely remove the crankshaft from the engine and subject the crankshaft journals to the action of grinding or lapping and/or polishing tools forming part of a separate and distinct lapping and polishing machine. While efficient, such prior methods were extremely slow and costly.

My method provides for abrading the journals of an engine crankshaft without removing the same from the engine and while operatively associated with the main bearings of the engine block and with the connecting rod bearings of the engine. I accomplish this by substituting thin abrading liners of the type shown in my co-pending U. S. application Ser. No. 164,389, filed September 17, 1937, now Patent No. 2,141,823, dated Dec. 27, 1938, for the bearing liners of the main and connecting rod bearings of the engine, and rotating the engine crankshaft so as to subject the journals of the latter to the action of said abrading liners for truing and/or polishing said journals. In this way, I am able to accomplish efficient and accurate truing and polishing of the crankshaft journals under the actual conditions of engine operation and in an expeditious and economical manner. As is the case with ordinary bearing liners, the abrading liners consist of a pair of semi-cylindrical members adapted to seat against the bore of the bearing and having secured or bonded to their inner surfaces suitable granular abrading material, such as emery or carborundum, which engages the crankshaft journal. The abrading liner sections are preferably of the same width or length as the bearing block and its cap, and are seated in contacting relation with each other at their end or longitudinal edges. As with bearing liners, the abrading liners are preferably provided with means to assure retention of the same in the correct positions with respect to each other and the bearing and against turning with the crankshaft journal, such as cooperating elements of the abrading liners and the bearings. The abrading liner sections are preferably constructed of relatively stiff and strong material, such as steel

or other suitable metal, which will effectively resist distortion and destruction during the abrading operation.

Other objects and features of the invention will become apparent from the following description when considered in connection with the accompanying drawing, in which:

Figure 1 is a fragmentary sectional view showing an engine whose crankshaft bearings are provided with abrading liners for abrading the crankshaft journals in accordance with the present method.

Figure 2 is an enlarged fragmentary section taken on line 2—2 of Figure 1 at one side of a connecting rod bearing; and

Figure 3 is an enlarged perspective view of one of the abrading liner sections employed in carrying out the present method as shown in Figures 1 and 2.

Referring in detail to the drawing, 5 indicates an engine cylinder block having pistons 6 reciprocable in the cylinders thereof. As usual, the engine crankshaft 7 has a plurality of spaced journals 8 mounted in bearings 9 of the engine block 5, and the cranks of said crankshaft have journals 10 engaged in bearings 9a provided on the lower ends of connecting rods 11, to the upper ends of which the pistons 6 are attached. As is well known in the art, each of the bearings 9 and 9a includes a half bearing or bearing block 20 integral with the cylinder block 5 and the connecting rod 11 as respectively indicated at 12 and 12a, and a separate half bearing or bearing cap 13 and 13a detachably bolted as at 14 and 14a to the bearing block 12 and 12a, respectively. 30 As is also well known in the art, the bearings 9 and 9a are usually provided with thin bearing liners which are seated loosely in the bearings and clamped therein by the bolts 14 or 14a by which the several sections of the bearings are 40 clamped together. Each of these bearing liners usually consists of a pair of semi-cylindrical members composed of a thin outer shell adapted to seat against the bore of the bearing and having bonded to its inner surface suitable anti-friction 45 material which engages the crankshaft journal. The bearing liner sections are usually the same width or length as the bearing and are seated in contacting relation with each other at their end or longitudinal edges.

In accordance with the present invention, the bearing liners of the bearings 9 and 9a are removed and abrading liners conforming in general size and shape to said bearing liners are substituted for the latter, such abrading liners each con- 50 55

sisting of a pair of semi-cylindrical members 15 composed of a thin outer shell adapted to seat against the bore of the bearing and having secured or bonded to its inner surface granular 5 abrading material 16 such as emery or carborundum which bears upon the crankshaft journal. These abrading liner sections are the same width or length as the bearing and are seated in contacting relation with each other at their end or 10 longitudinal edges. Some suitable means such as is usually provided in connection with the bearing liners, is provided to assure retention of the abrading liner sections in the correct positions with respect to each other and the bearing. In 15 the construction illustrated by way of example, this means consists of a lug 17 struck outwardly from an end of each abrading liner section and adapted to engage in a recess 18 of the associated bearing member and to abut the adjacent end of 20 the coating bearing member as shown clearly in Figure 2. In this way the abrading liner sections are also held against turning with the crankshaft journal, the thin outer shell of the abrading liner section being constructed of relatively stiff and 25 strong material such as suitable sheet metal, which will effectively resist destruction and distortion upon rotation of the crankshaft.

After the abrading liners have been placed in the bearings and clamped or bolted therein by 30 the bolts 14 and 14a, crankshaft 1 is rotated by any suitable or preferred means so as to subject the journals of the crankshaft to the abrading action of the abrading liners. As the abrading operation proceeds, the abrading liners may be 35 adjusted by means of suitable shim plates interposed between the bearing and the abrading liners, or thicker abrading liners may be substituted for those initially placed in the bearings, if found necessary. In the initial steps of the 40 method, comparatively coarse abrading elements or liners are employed, and after the crankshaft journals have been abraded sufficiently to true the latter, the journals may be finally polished by substituting further abrading liners of a finer 45 character or wherein the abrading material is of a finer texture. Of course, it is necessary to rotate the crankshaft for a sufficient length of time after the abrading liners are placed in the bearings. Upon completing the polishing operation, the abrading liners are removed and the 50 bearings are ready for reception of new bearing liners. All of these operations are performed

without removing the crankshaft from the engine and without the necessity of a separate and distinct lapping and polishing means of expensive construction. By truing and polishing the crankshaft journals in the engine block and connecting rod bearings, accurate and efficient truing of the bearings is insured in a most expeditious and economical manner. The abrading liners may be individually manufactured in proper sizes and grades, or they may be formed at the 10 point of operation by cutting suitable blanks from sheet abrading material especially manufactured for the purpose. 5

From the foregoing description, it is believed that the nature of the present invention, as well 15 as its advantages, will be readily understood and appreciated by those skilled in the art.

What I claim as new is:

1. The method of abrading the main journal of an engine crankshaft without removing the latter 20 from the engine, which consists in substituting in the actual main engine bearing and for the bearing liner sections of said bearing, thin abrading liner sections composed of thin outer shells of stiff strong sheet material having abrading material bonded to their inner surfaces and corresponding in form and size to said bearing liner sections, securing said abrading liner sections in the bearing by the means which secures the bearing sections together so that the abrading material thereof contacts the surface of the crankshaft journal, and rotating the crankshaft while in the engine so as to subject its journal to the action 25 of said abrading liner sections. 30

2. The method of abrading the journal of an engine crankshaft, which consists in substituting in the actual crank pin bearing of the actual engine connecting rod and for the bearing liner sections of said bearing without removing said connecting rod or its piston from the engine, 40 thin abrading liner sections composed of thin outer shells of stiff strong sheet material having abrading material bonded to their inner surfaces and corresponding in form and size to said bearing liner sections, securing said abrading liner 45 sections in the bearing by the means which secures the bearing sections together so that their abrading material contacts the surface of the crankshaft journal, and rotating the crankshaft so as to subject its journal to the action of said 50 abrading liner sections. 45

FRANK POSTMA.
